(57) **CLAIM**

We claim the ornamental design for an electric motorcycle, as shown and described.

DESCRIPTION

FIG. 1 is a top, front, and left side perspective view of an electric motorcycle embodying our new design;
 FIG. 2 is a top, front, and right side perspective view thereof;
 FIG. 3 is a left side elevation view thereof;
 FIG. 4 is a right side elevation view thereof;
 FIG. 5 is a front elevation view thereof;
 FIG. 6 is a rear elevation view thereof; and,
 FIG. 7 is a top plan view thereof.
